CLAIM

The ornamental design for a bracket for a bathroom accessory, as shown and described.

DESCRIPTION

FIG. 1 is a top view of a bracket for a bathroom accessory, showing my new design;

FIG. 2 is a side view as seen from the bottom of FIG. 1.
FIG. 3 is an end view as seen from the right of FIG. 1.
FIG. 4 is a sectional view taken in the direction of the arrows on line 4—4 of FIG. 1;

FIG. 5 is a sectional view taken in the direction of the arrows on line 5—5 of FIG. 1;

FIG. 6 is a fragmentary sectional view taken in the direction of the arrows on line 6—6 of FIG. 5.
